UNITED STATES PATENT OFFICE.

GEORG BORNSCHEIN, OF BAUTZEN, GERMANY.

LAYING-ON AND REMOVING DEVICE FOR PLATEN PRINTING PRESSES.

Application filed May 18, 1921. Serial No. 470,532.

To all whom it may concern:

Be it known that I, GEORG BORNSCHEIN, a citizen of Germany, residing at 16 Moltkestrasse, Bautzen, Germany, have invented 5 certain new and useful Improvements in a Laying-On and Removing Device for Platen Printing Presses, of which the following is a specification.

The invention relates to a laying-on and 10 removing device for platen printing presses.

According to the invention the gripper or sucker grips the sheet on the laying-on table positively, draws it downwards on to the surface of the platen, holds it firmly during 15 printing and after printing transfers it to a delivery device, disposed above the laying-on table, which delivers the sheet to a receiving table. The backward and forward movement of the grippers is preferably effected by means of levers hinged to the platen, these levers being rocked by a toothed wheel also provided on the platen. The toothed wheel is driven by a rack hinged to the machine frame, the toothed wheel being 20 adapted to roll on the rack on the movement of the platen. The connecting rod between the levers and the toothed wheel is preferably adjustably connected to the levers so that the magnitude of the oscillatory movement of the levers can be adjusted, whereby 25 the oscillatory movement may be made to suit the size of the sheets to be printed.

The device has the advantage that the laying-on and removal of the sheet is effected 30 entirely automatically. During the whole operation the sheet to be printed or the printed sheet is under the observation of the layer-on so that it may be observed continuously during the operation.

40 The device has in addition the advantage that in consequence of the variability of the path of the sheet the machine may be run at a higher speed for smaller sheets by reason of the shorter path. The provision of laying-on marks on the operative surface of the platen is unnecessary.

In the accompanying drawing is illustrated by way of example a constructional form of the subject of the invention.

50 Figure 1 shows a side elevation of the essential portion of a platen printing press which is the subject of the invention, the platen being in the laying-on position.

Figure 2 shows a side elevation of the 55 platen printing press with the platen in

the printing position, the delivery position of the platen being indicated by chain dotted lines.

Figure 3 shows to a larger scale in side elevation with a section through the supporting plate for the grippers, the operation of the grippers by a non-circular shaft.

Figure 4 shows the drive for this non-circular shaft to a smaller scale, this being a section on the line A—B of Figure 5.

60 Figure 5 shows a plan corresponding to Figure 4.

Figure 6 shows a section of the corner of the platen with a front view of the block guided therein, to which the gripper supporting plate is secured.

Figure 7 shows a cross-sectional view through the cam and its associated parts, and

Figure 8 shows an enlarged side elevation of the platen and form in closed position.

75 On the frame 1 of the platen printing press, is provided the platen 2. It is operated and advanced on the frame by the driving pulley 3 through the medium of the connecting rod 4 in the known manner. The movement of the platen 2 is controlled by the pin 5, which is rigidly secured to the machine frame 1 and engages in a slotted guide 6, rigidly connected to the platen. To each side of the platen a curved lever 7 is hinged 80 at 8. The two levers 7 are rigidly connected together by a shaft passing across the machine. One of the levers is provided with a slotted plate 9. In this is adjustably mounted a bolt 10; this bolt can be locked in the slotted plate by a winged nut 11. To the bolt 10 is hinged one end of the connecting rod 12, the other end of the rod being pivotally connected to the toothed wheel 13. The toothed wheel 13 is rotatably 85 mounted on the platen 2 and engages with a rack 14, which is pivoted to the machine frame at 15.

90 On the movement of the platen the toothed wheel 13 rolls down the rack 14 and consequently rocks the levers 7 by means of the connecting rod 12. The rocking movement of the levers 7 is greater or smaller, according as to whether the bolt 10 is adjusted in the slotted plate 9 at a longer or shorter distance from the fulcrum 8 of the levers 7.

100 Blocks 17 guided in the operative face of the platen are linked to the ends of the levers 7 by means of links 16. To these blocks is secured a plate 18 (Figures 4 and 5) passing 105

110

transversely across the operative face of the platen, this plate having the grippers 19 pivotally connected thereto (Figures 1, 3, 4, and 5).

5 These grippers 19 are held in the closed position by springs 20. They can be moved into the open position against the action of these springs by the non-circular shaft 21, (Figure 3).

10 For driving this shaft 21 there is rigidly secured at one end thereof a lever 22 having a number of arms. One arm of this lever engages in a recess 23 of the block 17, and projects into a longitudinal slot 24 in the 15 block, leading to the recess 23.

A groove 25 is formed in the lateral edge of the platen, to guide the block 17 and a blade spring 26 is arranged in the groove so as to project over the bottom of the groove.

20 On the movement of the block from the lower edge of the platen to the upper-edge thereof, the downwardly directed arm of the lever 22 strikes against the spring 26, and is thus turned in a clockwise direction. The 25

arm of the lever which up to the present has been horizontal is thus moved into an almost vertical position. The return movement of the lever and the consequent turning of the non-circular shaft 21 in a anti-clockwise direction is effected by the lever 27. This

30 is pivotally mounted on the pivot 28 (Figures 1 and 2) and is rigidly connected to the lever 29 to which is hinged the connecting rod 30. The end of this connecting rod carries a roller 31 which is guided on a cam 32 on the driving pulley 3. As shown in Figure 7, the crank pin of the driving pulley 3, which moves the connecting rod 4 for the platen 2 back and forth, is lengthened and the cam 32 is mounted fast thereon, in such a 35 way that said cam in no way hinders the movement of the connecting rod 4.

Referring to Figure 8, it will be seen that the grippers 19 do not strike against the 40 form when the platen is in its printing position by virtue of the fact that these grippers are not as thick as the difference between the height of the type 36 and the height of the closing material 37.

45 In the position of the lever 22 shown in full lines in Figure 4 the flat surface of the shaft 21 is at the side and also in the chain-dotted position shown in Figure 3.

In this position the gripper is open and 50 ready to receive a sheet. If the lever 22 is brought into the chain-dotted position in Figure 4 by the lever 27 the flat surface of the shaft 21 is at the top 55 in a horizontal position. In this position 60 the gripper is closed by the action of the spring 20 and grips the sheets inserted therein.

The operation of the device is as follows:

65 The sheet on the laying-on table 33 is moved under the gripper 19. As soon as the

platen 2 commences its movement towards the impression plate, the grippers are closed.

By reason of the movement of the platen, the toothed wheel 13 rolls down the rack 14. It rocks the levers 7, as above described 70 so that the grippers, hinged to these levers, and the sheet are drawn over the surface of the platen into the press.

When the platen has almost reached the printing position the rack 14 and the toothed 75 wheel 13 have assumed such a relative position, that on the further movement of the platen to the printing position no further movement of the levers 7 and the grippers 19 takes place.

80 After the printing has been completed the platen is swung back in the known manner. During this return movement of the platen the levers 7 are again swung backwards and consequently also the grippers, and with 85 these the sheet, are moved upwards; the end of the sheet projecting beyond the upper edge of the platen is thus brought into the delivery device 34, provided above the laying-on device, which consists of rollers and 90 one or more delivery bands. As soon as the platen 2 reaches the chain-dotted position in Figure 2, the sheet is gripped by the delivery device and transferred to the receiving table 35.

95 Finally the platen 2 again returns to the position illustrated in Figure 1 and during the latter position of this movement the grippers 19 have again been opened by the spring 26. The device is now ready for the 100 commencement of another operation.

I claim:—

1. A laying-on and removing device for platen printing presses the arrangement of grippers adapted to grip the sheet on the 105 laying-on table means for positively moving the grippers with the gripped sheet downwardly over the platen so that the upper edge of the sheet coincides with the upper edge of the platen and to hold the sheet during the printing operation and after the printing operation to transfer them upwardly over the platen, a delivery device disposed above the laying-on table for delivering the sheet from the grippers to the 110 receiving table substantially as described and represented hereinbefore.

2. A laying-on and removing device for platen printing presses the arrangement of grippers adapted to grip the sheet on the 115 laying-on table, levers hinged to the platen, a toothed wheel pivoted to the platen and rocking the levers, a rack hinged to the machine frame, the wheel gearing with this rack, a delivery device disposed above the 120 laying-on table for delivering the sheet from the grippers to the receiving table substantially as described and represented hereinbefore.

3. A laying-on and removing device for 130

platen printing presses, the arrangement of grippers adapted to grip the sheet on the laying-on table, levers hinged to the platen, a toothed wheel pivoted to the platen, a rod with one end adjustably connected to the levers and with the other end hinged to the wheel, a rack hinged to the machine frame,

the wheel gearing with this rack, a delivery device disposed above the laying-on table for delivering the sheet from the grippers to the receiving table substantially as described and represented hereinbefore.

In testimony whereof I affix my signature.

GEORG BORNSCHEIN.
